SYLVANIA.

INSULATOR-SUPPORT.

1,210,686.

Specification of Letters Patent.

Patented Jan. 2, 1917.

Application filed April 6, 1916. Serial No. 89,366.

To all whom it may concern:

Be it known that I, CHARLES L. PEIRCE, Jr., a citizen of the United States, and a resident of Pittsburgh, in the county of Allegheny and State of Pennsylvania, have invented certain new and useful Improvements in Insulator-Supports, of which the following is a specification.

My invention relates to insulator supports particularly to that class in which a thimble structure of comparatively thin sheet metal is secured to a bracket member or pin of heavier material such as cast iron or sheet metal. In supports of this class the thimble structure is frequently sub-divided by longitudinal slits or gaps in order that the sections thereof may yield radially to prevent breakage of or the introduction of strains into the insulator and also to yield during expansion and contraction during changes of temperature. During ordinary service of an insulator these thimble structure sections will retain their springiness and elasticity but, when under extraordinary conditions the sections may become permanently bent so that the insulator will become loosened. An example of such extraordinary service is where wires are dead-ended on the insulator and exert considerable lateral pull thereon against the corresponding thimble sections.

The object of my invention is to provide improved means which will not interfere with proper yielding of the thimble structure when the insulator is applied but which, after seating of the insulator, will prevent the sections from giving or becoming permanently bent and which will securely lock the insulator against rotation or displacement during service yet which will permit ready removal of the insulator when desired.

My improved means is preferably in the form of wedge mechanism which is actuated by an insulator during its final seating movement and which acts to expand the thimble sections to clamp them securely against the insulator inner sides.

On the accompanying drawing I have shown an insulator support in the form of a bracket to which my invention has been applied.

In the drawing Figure 1 is a side elevational view of the support with the thimble structure and locking attachment in unlock-
ing position, the thimble structure being partly in section, Fig. 2 is a similar view

showing an insulator applied and the attachment and the locking mechanism in locking position, and Fig. 3 is a top view of the thimble structure with the wedge member removed.

The support shown comprises the U-shaped bracket member whose body part 10 is of arched or U-shaped cross-section, the limbs 11 and 12 being parallel or at angles with each other but at the inner end of the body being brought together to form the seat *e* of circular cross-section. Any suitable means may be provided for supporting the bracket to the support. As shown wings 13 are provided at the inner end and have the bolt holes 14. The thimble structure T shown comprises the two halves 15 and 16 of semi-circular cross-section secured at their bases to the seat *e* by a rivet 17. The halves or sections 15 and 16 are separated a distance at their vertical edges by gaps 18 and 19, such gaps permitting radial yield of the sections during application of insulators. During service under ordinary conditions the sections will retain their springiness and elasticity and will clamp the insulator sufficiently to hold it in place. However, under extraordinary conditions and strain the sections may become permanently bent in which case the insulator becomes loosened and the efficiency of the structure is destroyed. The mechanism I have shown for preventing such permanent bending and for firmly keeping the thimble and insulator locked together comprises a wedge member or button 20 which co-operates with inclined walls 21 and 22 extending from the thimble halves 15 and 16. As shown, these walls 21 and 22 are integral with the thimble halves and are in the form of tongues bent diagonally downwardly into the thimble structure with their ends 23 and 24 deflected radially outwardly against the thimble halves to support the walls 21 and 22 in their diagonal position. The wedge button 20 has a head 25 which extends over the top of the thimble to limit the inward movement of the wedge button, and the top of the head is rounded to receive the top *a* of the bore of insulators I. At its lower end the wedge button has the enlargement 26 for preventing accidental removal of the button from the thimble and for limiting the outward movement thereof. In Fig. 1 the button is in its upper position, 110

its head 25 being a distance above the top of the thimble. Now when an insulator is applied as shown in Fig. 2, the top *a* of the insulator bore will eventually encounter 5 the head of the wedge button and during final seating of the insulator the wedge button will be forced downwardly between the inclined walls 21 and 22 of the thimble halves, and these halves will be spread apart 10 and securely clamped against the inner sides of the insulator to lock the thimble structure and insulator securely together. Such clamping engagement will not destroy the yielding properties of the thimble sections 15 but will prevent permanent bending of the thimble sections under extraordinary load or strain. Neither will it interfere with the ready removal of the insulator for immediately after the insulator is started to be un- 20 screwed its pressure against the wedge button will be released and the thimble sections unclamped from the insulator whereafter the insulator can be readily removed.

The wedge button may be of metal, wood, 25 fiber, or any other suitable material and may be of cylindrical, polygonal, or other cross-section. Instead of having the thimble structure divided only into two parts as shown, it could be further sub-divided and 30 a corresponding number of inclined walls extended therefrom to coöperate with the wedge button. Other changes and modifications are also possible which would still come within the scope of the invention and 35 I do not therefore desire to be limited to the precise constructions and arrangements shown and described.

I claim as follows:

1. In an insulator support, the combination with an insulator receiving end divided longitudinally into sections having internal wedge abutments, a wedge member associated with said abutments, and a head for the wedge member overhanging the insulator receiving end to limit the downward movement of the wedge member between the abutments.
2. In an insulator support, the combination with an insulator receiving end divided longitudinally into sections having internal wedge abutments, a wedge member associated with said abutments, a head for the

wedge member overhanging the insulator receiving end to limit the downward movement of the wedge member between the abutments, and an enlargement or knob at the lower end of said wedge member for limiting the upper movement thereof. 55

3. In an insulator support, the combination with a hollow radially expansible insulator receiving end having wedge abutments, a wedge between said abutments, and upper and lower stop abutments on said wedge for limiting the movement thereof, said upper stop abutment being in position to be engaged by the top of an insulator applied to said end and to be shifted downwardly with the insulator to exert wedging action on the wedge abutments. 65

4. In an insulator support, the combination with a yieldable sheet metal threaded insulator receiving end, sections of said sheet metal end being deflected diagonally inwardly to form opposed wedging surfaces, and a wedge member between said surfaces 75 in the path of an insulator applied to said end to be forced between said wedging surfaces to cause the end to expand and clamp the insulator.

5. In an insulator support, the combination with a threaded sheet metal insulator receiving end sub-divided vertically into sections, tongues deflected diagonally inwardly from said sections to form wedging surfaces, and a wedge between said surfaces in the 85 path of an insulator applied to said end to be shifted along said wedge surfaces to cause radial separation of the sections into clamping engagement with the insulator. 80

6. In an insulator support, the combination with a threaded sheet metal insulator receiving end sub-divided vertically into sections, tongues deflected diagonally inwardly from said sections to form wedging surfaces, a wedge between said surfaces in the path of 95 an insulator applied to said end to be shifted along said wedge surfaces to cause radial separation of the sections into clamping engagement with the insulator, and abutments on said wedge for limiting its movements. 100

In witness whereof I hereunto set my hand this 26th day of February, A. D. 1916.

CHARLES L. PEIRCE, JR.
